(57) **ABSTRACT**

The present invention provides a new and distinct hemp cultivar designated as 'CW2A'.

13 Drawing Sheets

1

Latin name of genus and species: *Cannabis sativa* L.
Variety denomination: 'CW2A'.

BACKGROUND OF THE INVENTION

Cannabis is a genus of flowering plants that includes at least three species, *Cannabis sativa*, *Cannabis indica*, and *Cannabis ruderalis* as determined by plant phenotypes and secondary metabolite profiles. In practice however, *Cannabis* nomenclature is often used incorrectly or interchangeably.

Hemp, also known as industrial hemp, is a type of *Cannabis* plant grown specifically for the industrial uses of its derived products. Hemp by definition has no more than three-tenths of one percent (i.e., 0.3%) concentration of tetrahydrocannabinol (THC). THC causes psychoactive effects when consumed and is typically associated with marijuana (i.e., *Cannabis* with higher THC contents). Hemp extracts produced from industrial hemp, such as extracts produced from 'CW2A', have no such psychoactive effects due to their low THC content. Values of total CBD and total THC obtained from laboratory testing of dried mature female flowers may show variance that results from differing growing environments, sampling methodologies, and testing techniques.

The present invention relates to a new and distinct hemp (*Cannabis sativa* L.) cultivar designated as 'CW2A'. Whole-plant hemp extracts from 'CW2A' contain an assortment of phytocannabinoids (e.g., CBD), terpenes, flavonoids and

2

other minor but valuable hemp compounds that work synergistically to heighten effects of products produced from 'CW2A'. This synergistic effect is sometimes referred to as the "entourage effect". 'CW2A' extracts can be used to produce a variety of products, including liquid and capsule forms for oral administration, topical products, cosmetic products, infused beverages, sport products and hemp-infused pet treats.

Despite *Cannabis* being consumed since at least the third millennium BC, complete scientific corroboration for uses of CBD are still in their infancy. Industry reports suggest CBD is used for a variety of health and wellness purposes, including as a sleep aid, coping with daily stress, fighting anxiety, relieving pain, assisting with cognitive function and boosting immune health. Significant research is currently being conducted at a variety of laboratories on the use of CBD as it relates to epilepsy, Post-Traumatic Stress Disorder (PTSD), cancer, autism, neuroprotection, anti-inflammatory effects, anti-tumor effects and anti-psychotic effects.

'CW2A' is a selection resulting from controlled-crosses using hemp germplasm from different regions of the United States. The primary goal of the breeding program was to develop a new hemp variety with high cannabidiolic acid (CBDA) concentrations and low tetrahydrocannabinolic acid (THCA) concentrations in its mature female flowers. Of the females tracing back to the original cross, the healthiest and most vigorous individual that showed no monoecious tendencies without stress manipulation was chosen to be 'CW2A'.

The new cultivar of 'CW2A' was asexually reproduced via stem cuttings from vegetative and/or flowering plants, and cloning by the inventor at the inventor's greenhouses, nurseries, fields and/or facilities in Colorado Springs, Colo. and Wray, Colo. Asexual clones from the original source have been tested in greenhouses, nurseries, and/or fields. The properties of each clone from this cultivar were found to be transmissible by such asexual reproduction. The cultivar is stable and reproduces true to type in successive generations of asexual reproduction (i.e., clones from 'CW2A' are uniform).

BRIEF SUMMARY OF THE INVENTION

This invention relates to a new and distinctive hemp cultivar designated as 'CW2A'.

As used herein, the term "cultivar" is used interchangeably with "variety", "strain", and/or "clone".

The inventor reproduced progenies asexually by stem cutting from vegetative and/or flowering plants, and cloning. The plant has been and continues to be asexually reproduced by stem cutting from vegetative and/or flowering plants, and cloning at the inventor's greenhouses, nurseries, fields and/or facilities in Colorado Springs, Colo. and Wray, Colo.

DESCRIPTION OF THE DRAWINGS

The accompanying color photographs depict characteristics of the new 'CW2A' plants as nearly true as possible to make color reproductions. The overall appearance of the 'CW2A' plants in the photographs is shown in colors that may differ slightly from the color values described in the detailed botanical description.

FIG. 1 shows an overall view of the 'CW2A' indoor plant at the early to mid vegetative growth stage with lateral branches and further intermodal growth as shown from above.

FIG. 2 shows an overall view of the 'CW2A' indoor plant during the mid to late vegetative growth stage as shown from the side.

FIG. 3 shows an overall view of the 'CW2A' indoor plant during the mid to late vegetative growth stage as shown from the side.

FIG. 4 shows an overall view of the 'CW2A' indoor plant at the early to mid flowering stage as shown from the side.

FIG. 5 shows a close view of flowers of the 'CW2A' indoor plant at the early to mid flowering stage.

FIG. 6 shows another close view of flowers of the 'CW2A' indoor plant at the early to mid flowering stage.

FIG. 7 shows an overall view of the 'CW2A' outdoor plant at the mid vegetative growth stage as grown in the field.

FIG. 8 shows a close view of flowers of the 'CW2A' outdoor plant at the early to mid flowering stage as grown in the field.

FIG. 9 shows an overall view of upper part (including flowers) of the 'CW2A' outdoor plant at the early to mid flowering stage as grown in the field.

FIG. 10 shows an overall view of the 'CW2A' outdoor plant at the harvest maturity as grown in the field.

FIG. 11 shows an overall view of upper part (including flowers) of the 'CW2A' outdoor plant at the harvest maturity as grown in the field.

FIG. 12 shows a close view of flowers of the 'CW2A' outdoor plant at the harvest maturity as grown in the field.

FIG. 13 shows another close view of flowers of the 'CW2A' outdoor plant at the harvest maturity as grown in the field.

DETAILED BOTANICAL DESCRIPTION

'CW2A' has not been observed under all possible environmental conditions, and the phenotype may vary significantly with variations in environment. The following observations, measurements, and comparisons describe this plant as grown at Wray, Colo., when grown in the greenhouse, nursery or field, unless otherwise noted.

Plants for the botanical measurements in the present application are annual plants. In the following description, the color determination is in accordance with The Royal Horticultural Society Colour Chart, Sixth Edition (2015), except where general color terms of ordinary dictionary significance are used.

'CW2A' is a fertile hybrid derived from a controlled-cross between proprietary cultivar '1AC' as the female parent (i.e., pollen accepter) and another hemp plant as the male parent (i.e., pollen donor) originating from a feral hemp (a.k.a. ditch weed) population in Colorado with an unknown cannabinoid content ("Feral Male Parent").

Breeding History of the Female Parent. The lineage of proprietary female parent '1AC' comprises four generational crossings. The first crossing was made between a parental female from a cutting of *Cannabis sativa* L. originating in Colorado of unknown parentage ("First Female F₀") with a parental male plant ("First Male F₀") which originated from a feral hemp population in Colorado with an unknown cannabinoid content. Of the resulting progeny, 40 seeds were germinated and developed into 24 female ("F₁ Females") and 16 male ("F₁ Males") plants.

For the second crossing, an egg donor from a female clone of *Cannabis sativa* L. with unknown genealogy ("Second Female") was crossed to a healthy vigorous F₁ Male from the first cross. Of the resulting offspring, twenty seeds were germinated of which 70% were female ("F₂ Females") and 30% were male ("F₂ Males").

For the third crossing, a single F₂ Female was chosen and crossed with a sibling of First Male F₀. Of the resulting progeny, fifty seeds were germinated. Twenty-five seedlings were female ("F₃ Females") and 25 were male ("F₃ Males").

The fourth generation was produced by crossing two F₃ Females that displayed the most vigor and health. Both F₃ Females chosen for the cross were short and squat in stature, had medium to broad leaf structure with tight internodes of about 1/2 inch, and displayed a 70-75 day flowering maturity after flowering initiated. The F₃ Female was chosen as the egg donor ("F₃-e") for the fourth generation. The F₃ female was also chosen as the pollen donor ("F₃-p") for the fourth generation. The F₃-p female was induced to produce male flowers, thus generating pollen, using heat and erratic photoperiod stress techniques. F₃-e was pollinated by F₃-p and generated progeny (F₄) that were all female with slightly different characteristics. All F₄ plants exhibited *indica*-dominant traits such as medium to broad leaf structure, short squat overall growth habit, and tight internodes with full flower maturity taking roughly 65-70 days after flowering initiated. About 90% of all F₄ plants exhibited resistance to pests and diseases and showed great health and vigor throughout the entire lifecycle. Few plants displayed white and/or yellow coloration similar to marbling on the leaves.

Of these F₄ females, the healthiest and most vigorous individual was chosen to be '1AC'.

Breeding History of the Male Parent. The Feral Male Parent of 'CW2A' was the most vigorous and healthy male with broad, palmately compound leaves and squat stature at maturity ("indica-dominant") which germinated from a feral hemp population. Ten seeds of the resulting offspring were germinated. Of the ten seeds, six were male and four were female. Ninety percent of all individuals exhibited resistance to pests and diseases and showed great health and vigor throughout the entire lifecycle. Nearly all of the males grew taller than the females and exhibited medium to broad leaf structure similar to *indica/sativa* hybrid characteristics. The Feral Male Parent is not a genetically modified organism.

Crossing of Parental Lines. '1AC' was crossed to the Feral Male Parent and all of the resulting females displayed long and slender leaflets, leaves, and overall growth pattern ("sativa-dominant"). Of the females, 75% exhibited monoecious characteristics without stress manipulation. All females showed premature flowering without a change in light duration; although change in light duration to 12 hours of light and 12 hours of dark within a 24-hour period induced all females into a distinct flowering cycle. Of these females, the healthiest and most vigorous individual, that showed no monoecious tendencies without stress manipulation was chosen to be 'CW2A'.

TABLE I

General	
Characteristics	New Variety
Plant life forms	An herbaceous plant (herb)
Plant growth habit	An upright, dioecious annual plant with hermaphroditic tendencies, and at maturity 1-4 meters in height depending on growth conditions
Plant origin	Having no hermaphroditic (monoecious) tendencies without stress manipulation
Plant propagation	Female progeny of a cross between '1AC' Female Parent and Feral Male Parent
Propagation ease	Asexually propagated by cutting and cloning such as vegetative stem cuttings as well as stem cuttings from flowering plants
Propagation condition	Easy
Height (Unit: meter and/or feet)	Adventitious root structures readily form from stem tissue when submerged in rooting media, including soil, rockwool, aeroponics, etc., when adequate amounts of oxygen and moisture are supplied, and ambient temperatures are between 55-75 degrees Fahrenheit with appropriate lighting conditions.
Width (Unit: meter)	1-4 m at maturity
Plant vigor	Height and shape depends on planting pattern such as planting date and density. With about 2 feet or less close spacing between plants, plants can be up to 10 feet tall at maturity with thinner pseudospike flower characteristics. Generally, plant height is twice as much as plant width.
Time to Harvest	100-135 days
Resistance to pests or diseases	Resistant to common viruses and fungal diseases Susceptible to molds and mildews if grown indoors without proper ventilation and constantly

TABLE I-continued

General	
5	Genetically-modified organism
10	Characteristics
15	Plant life forms
20	Plant growth habit
25	Plant origin
30	Plant propagation
35	Propagation ease
40	Propagation condition
45	Height (Unit: meter and/or feet)
50	Width (Unit: meter)
55	Plant vigor
60	Time to Harvest
65	Resistance to pests or diseases
	Genetically-modified organism

TABLE II

Leaf/Foliage	
Characteristics	New Variety
Leaf arrangement	Opposite in early vegetative growth stages especially on main axis if grown from seed
55	A tendency toward alternate arrangements on axillary branches once the flowering stage begins or when taken as a vegetative cutting typically observed
60	Phyllotaxy depends on growth conditions and on whether individuals are derived from vegetative or seed propagation
Leaf shape	Palmately compound
Leaf structure	Serrated margins, lightly acicular to lanceolate leaflets, tapering to an acuminate apex

TABLE II-continued

Leaf/Foliage	
Leaf margins	Jaggedly serrate with each tooth apex angled toward leaflet apex Apical side of tooth is concave and basal side of tooth is convex
Leaf hairs	Absent
Leaf length with petiole at maturity (Unit: cm or inches)	12-24 cm
Petiole length at maturity (Unit: cm)	4.2-8.0 cm
Petiole color (RHS No.)	Very slightly lighter (whiter) than RHS 144A
Anthocyanin color and intensity in Petioles	RHS 59A to 187A and 187B when present Anthocyanin coloration ranges from total absence to minute but pronounced mixture with normal green coloration on adaxial surface of petiole during vegetative growth stage During flowering stage, anthocyanin pigmentation on petioles of so called fan leaves intensifies and covers both adaxial and abaxial surfaces; Darker adaxial surfaces are still RHS 59A to 187A; Abaxial surfaces are lighter and less densely colored with a range of coloration RHS 184A; to 180A; to 178A through 178B; to 176A
Stipule length at maturity (Unit: cm)	0.4-0.9 cm
Stipule shape	Up to 1.0 cm, spinose with a wider base about 1.0 mm or more thick tapering to spinose tip Light green center with white green edges and a folded, v-shape in cross section Sometimes curvaceous growth
Stipule color (RHS No.)	Green portions of stipule vary from RHS 143A to the light yellow white of the edges RHS 4D
No. of leaflets	3-5 in immature plants, as many as 9 at maturity
Middle largest (longest) leaflet length (Unit: cm)	7-15.9 cm
Middle largest (longest) leaflet width (Unit: cm)	1.5-2.0 cm
Middle largest (longest) leaflet length/width ratio	About 4:1-8:1
No. teeth of middle leaflet	19-29
Leaf (upper side-adaxial) color (RHS No.)	RHS 137A before flowering stage Very close to (a little darker/bluer) RHS NN137A during flowering stage
Leaf (lower side-abaxial) color (RES No.)	Yellow in late flowering stage Between RHS 146D and RHS 147C before flowing stage Between RHS NN137D and RHS 147B during flowering stage
Leaf glossiness	Very slight sheen, but not glossy Midvein is straight down the middle of each leaflet. Secondary veins are percurrent, branched alternately from midvein, and grow to tooth apex
Vein/midrib color (RHS No.)	RHS 143C
Aroma	An earthy aromatic herbal smell with a hint of citrus/pine scent and a general sweetness

TABLE II-continued

Leaf/Foliage	
5 Characteristics	Parental variety (1AC) (Female plant)
Leaf arrangement	Alternate with short internodes during early vegetative growth stages especially after cloning Sometimes opposite (seedling vegetative stage) and whorled (flowering stage) leaf positioning depending on growth conditions and vegetative or seed propagation Phyllotaxy depends on growth conditions and on whether individuals are derived from vegetative or seed propagation
10	15
Leaf shape	Palmately compound
Leaf structure	Serrated, lanceolate, pinnately veined leaflets with a medium to dark green upper surface and light green to white green lower surface. Broader leaflets than CW2A
20	Leaf margins
	Plane with tooth apices angled toward leaflet apex Jaggedly serrated when leaves are immature, developing into not so jaggedly serrated when leaves/leaflets are mature Both apical and basal side of tooth are generally convex
25	Leaf hairs
	Absent
	Typically 3"-7" inches.
30	Leaf length with petiole at maturity (Unit: cm or inches)
	Up to 10" inches in the field with optimal growing conditions and at peak vegetative growth
	5.1 cm-10.2 cm depending on leaf type (on axillary branch node vs main axis, subtending inflorescence, immature/mature, etc.)
	Between RHS145A and 145B
35	Petiole color (RHS No.)
	Anthocyanin color and intensity in Petioles
	Stipule length at maturity (Unit: cm)
40	Stipule shape
	<1 cm
	Linear with slight curvaceous growth. Sometimes slightly wider than those in CW2A and occasionally flower primordia containing a thin white filament hair similar to a mature stigma are found
45	Stipule color (RHS No.)
	No. of leaflets
	Middle largest (longest) leaflet length (Unit: cm)
50	Middle largest (longest) leaflet width (Unit: cm)
	Middle largest (longest) leaflet length/width ratio
	No. teeth of middle leaflet
	Leaf (upper side-adaxial) color
	Leaf (lower side-abaxial) color (RES No.)
55	Leaf glossiness
	Vein/midrib shape
60	
	Slightly glossy, especially at maturity
	Midvein is straight down the middle of each leaflet.
	Secondary veins are percurrent, branched alternately from midvein, grow to tooth apex with

TABLE II-continued

Leaf/Foliage	
Vein/midrib color (RHS No.)	some forming loops to other secondary veins, and more apparent tertiary venation, especially in mature leaflets RHS 145C
Aroma	A pleasantly earthy aromatic, strong, peculiar smell with a hint of pine scent

TABLE III

Characteristics	New Variety
Stem shape	Round at maturity Very slightly squared in immature axillary branches and at immature growth stages Finely pubescent and longitudinally furrowed in conjunction with the slightly square shape In later vegetative stages, still generally rounded in appearance with slight furrowing on more recent stem growth Older growth now fuller with lower parts of main stem and oldest branches now with slightly woody appearance and outer texture
Stem diameter at base (Unit: cm)	1.5-4 cm often multiple stems with thinner diameters, depends on nature of initial cutting material
Stem color (RHS No.)	Green portions between RHS 144A and 146A at vegetative maturity and during flowering, woody colored tan lower portions of stem are close to 156A-156D
Stem pith type	This is highly dependent on the age and/or maturity of the stem Most mature main stem pith is thick to woody
Characteristics	Parental variety (1AC) (Female plant)
Stem shape	A smooth or slightly longitudinally furrowed texture that can vary throughout the plant. Rigid, straight or flexuous Canescent, scabrous, or rough textured in late growth stage
Stem diameter at base (Unit: cm)	3.0-12 cm in outdoor plants
Stem color (RHS No.)	Immature RHS 146D Mature RHS 143C
Stem pith type	Moderate to thick

TABLE IV

Inflorescence (Female/Pistillate Flowers)	
Characteristics	New Variety
Flowering (blooming) habit	CW2A produces pistillate flowers in axils at nodal points along main axis and lateral branches for most of the vegetative growth period As flowering begins to develop, these start to become more prolific clusters of individual flowers that appear on increasing branching growth from axillary buds

TABLE IV-continued

Inflorescence (Female/Pistillate Flowers)	
5	emerging from increasingly short internodes on both the main and lateral axes Observations indicated a noted shift to this pattern between 57-73 days after vegetative clones were transplanted outdoors The pointed appearance of the terminal inflorescence buds probably contribute to the overall less dense popcorn appearance of floral clusters along the lateral and main axes
10	Some are quite full and denser more similar to 1 AC, but many are the looser popcorn appearance 100% with some exhibiting monoecious tendencies Above Apical portions of main and lateral axes Overlapping, Congested, touching, and sometimes stacked Hundreds to thousands flowers per plant Multitudinous, congested, with high concentrations on bushier wide inflorescence
15	Proportion of female plants Inflorescence position
20	Flower arrangement Number of flowers per plant
25	Flower shape Flower (individual pistillate) length (Unit: mm) Flower (compound cyme) Corolla diameter (Unit: cm)
30	Corolla Color (RHS No.) Bract shape
35	No defined corolla Apetalous pistillate flowers N/A Miniature leaf, trichomated, tips of leaflets emergent from dense floral clusters Leaflets number 3 or 5 with many bracts having 5 leaflets The base pair is nearly vestigial Bracts range in length from 2-7 mm or more depending on maturity of flowering spike Adaxial - darkest at tips between RHS 139A to lighter at base of leaflets RHS 147A Abaxial - between RHS 137B and 147B Bracteole is a short, scale-like, membranous piece of tissue, subtending (and nearly adhering to) the underside of pistillate flowers. It is very similar to the stipules of the plant, but wider, shorter, and buried within the densely clustered pistillate inflorescences and so, not immediately observable without dissection Like stipule, vibrant green streak in middle is very close to RHS 141C to thin white papery margins close to RHS 4D, 8D, 11D
40	Bract color (RHS No.)
45	Bracteole shape (general description)
50	Bracteole color (RHS No.)
55	Calyx shape (general description)
60	Calyx color (RHS No.)
65	Stigma shape

TABLE IV-continued

Inflorescence (Female/Pistillate Flowers)	
Stigma length (Unit: mm)	At flower maturity, the pistils senesce to a reddish-brown 4-11 mm Generally longer and thinner than '1AC' Pollination, and environmental factors effect state of stigma
Stigma color (RHS No.)	Freshly emergent, tips and papillae RHS 1C-1D to 2D and 4C Some have a slight vegetative greenish hue, RHS 144C to 145A When senesced, from a darker RHS 165A to a lighter 164A to 165B
Trichome shape	Capitate stalked glandular multiseriate/uniseriate trichomes, especially on flowering inflorescences and perigonial bracts Capitate Sessile glandular trichomes on stems, leaves, and bracts Cystolithic non-glandular trichomes on leaves
Trichome color (RHS No.)	RHS 4D and 155A and NN155A-NN155D, creamy color of varying saturation
Terminal bud shape	Terminal buds are naked, vegetative, and mixed depending on life stage (vegetative/flowering)
Terminal bud color (RHS No.)	Many emergent pistillate flowers, RHS NN137B through 143A-143C, 144B, N144C, 145A-145D, 157A-157D, Emergent bract leaflets RHS 147A Freshly emergent stigmas, tips and papillae RHS 1C-1D to 2D and 4C Some have a slight vegetative greenish hue, RHS 144C to 145A
Pedicel	Absent (sessile)
Staminate shape	Minute or reduced to absent (sessile) in pistillate flowers Present in staminate flowers
Sepal color (RHS No.)	RHS 10D at end near papery edges with vegetative streaks down center of each sepal, N144B to N144C, depending on maturity N/A
Pollen description	Light to Dark brown, mostly dark brown with speckling
Seed description	Seeds (achenes) are encased in trichomated leaf-like fused bract (perigonium), solitary, ovoid, and slightly compressed Pericarp is dry and brittle, finely reticulate; endosperm is fleshy; embryo curved; cotyledon is fleshy Seeds (achenes) are solitary, ovoid, 4-7 mm in length Typically, seeds weigh 0.01 g-0.02 g each Variation in seed size and color are observed due to environmental conditions
Marbling of seed	Medium
Petal description	Apetalous (petals absent in flowers, but sepals present on staminate flowers)
Characteristics	Parental variety (1AC) (Female plant)
Flowering (blooming) habit	Early flower primordia appear at the base of petioles, with a pair of white stigmas emerging from each perigonial bract. Pistillate compound inflorescences are congested pseudospikes with leaf-like bracts, leafy and compact, with the largest inflorescences present on dominant apical stems

TABLE IV-continued

Inflorescence (Female/Pistillate Flowers)	
5	Female flowers are small but numerous and take on the coloration present in the vegetation of the specimen (typically green); enclosed and surrounded by a fused calyx (perigonial bract), entire, beaked at the tip; unilocular ovary superior, sessile, with two long filiform stigmatic branches which are white upon emergence and later deteriorating to reddish-brown Flowers may form on the entire length of the stem; however, inflorescences are most conspicuous at the top of the plant. Flowers and inflorescences are covered with glandular trichomes 100%
10	Above
15	Proportion of female plants Inflorescence position
20	Flower arrangement
25	Number of flowers per plant
30	Flower shape
35	Flower (individual pistillate) length (Unit: mm)

55	Bracteole color (RHS No.)
60	Calyx shape (general description)
65	Calyx color (RHS No.)

TABLE IV-continued

Inflorescence (Female/Pistillate Flowers)	
Stigma shape	Short apical style with two long filiform stigmatic branches
Stigma length (Unit: mm)	At flower maturity, the pistils senesce to a reddish-brown 6-9 mm
Stigma color (RHS No.)	Pollination, and environmental factors effect state of stigma RHS 150A-150C or 151C-151D when freshly emergent to 8B when around maturity or past maturity, to 164A or 166A-166D or 174A-174B or 175D when senescent
Trichome shape	Capitate stalked glandular multiseriate/uniserrate trichomes, especially on flowering inflorescences and perigonial bracts Capitate Sessile glandular trichomes on stems, leaves, and bracts Cystolith non-glandular trichomes on leaves
Trichome color (RHS No.)	Variable Clear, white; translucent at first, as it matures, cloudy to amber as phytochemicals enter the trichome glandular head
Terminal bud shape	Terminal buds are naked, vegetative, and mixed depending on life stage (vegetative/flowering)
Terminal bud color (RHS No.)	Multicolored
Pedicel	Absent (sessile)
Staminate shape	Absent
Sepal color (RHS No.)	N/A
Pollen description	N/A
Seed description	Seed coat with solid pale grey or grey/brown/white to light - dark brown coloration when mature Seeds (achenes) are solitary, ovoid, 3-6 mm in length Seed weight is typically varied with masses within the range of 0.006 g-0.016 g
Marbling of seed	N/A
Petal description	Apetalous (petals absent in flowers)

TABLE V-continued

Other Characteristics	
5	Hardy to tolerate of moist and damp conditions without Branches are highly flexible. Typically, plants lean over more than 1AC check variety Plants are resistant to complete lodging Central stem is strong. Stem breakage usually does not occur About 30-50% of seeds shatter readily if plants are grown in field 95-99% Adventitious roots typically form day 5-day 14 Roots fill a two-inch pot completely in Day 21-35 Total CBD content: 4.50-6.24% Total THC content:Total CBD 0.13-0.27% Total CBD:Total THC (ratio) = 23:1

35			
40			

TABLE V

Other Characteristics	
Characteristics	New Variety
Time period and condition of flowering/ blooming	Female flower initiation occurs in plants when the daylight photoperiod has 14 hours of daylight hours within a 24-hour period, with 10 hours of continuous darkness during the nocturnal duration Timing of flowering is largely dependent (if not entirely) on photoperiod
Proportion of hermaphrodite plants	Lower (~10%) in vegetative clones More moderate in populations from seeds harvested from fields (segregating population and not necessarily selfed)
Hardiness of plant	Resistant to frost (without freezing rain) in early and late growth stages Resistant to cold in late vegetative and mature stages Hardy to tolerate of moist and damp conditions without showing stress Not tolerant to soil oversaturated with water for long periods

TABLE V-continued

Other Characteristics	
Total THC and CBD content at harvest maturity	content: 5-8% Total THC content: 0.2-0.3% Total CBD:Total THC (ratio) = 26:1

As used herein, the term “maturity”, “harvest maturity,” or “floral maturity” refers to the developmental stage at which the ‘CW2A’ plant is harvested. Persons having skill in the art will recognize maturity based on the plant’s morphologies. It is also good practice to conduct periodic cannabinoid content (i.e., potency) tests throughout the development of the plant to ensure that harvest occurs at maturity. The ‘CW2A’ plant is considered to be at harvest maturity when fan leaves begin to yellow, and when inflorescences begin to take on a ‘frosted’ appearance, as trichomes develop on calyxes and lower portions of bracts. If bracts and inflorescent parts turn overly yellow and/or if the ‘frosted’ appearance is visible from afar, this could indicate the plant is beyond maturity. The color of trichomes can also be used to determine maturity. Trichomes from the ‘CW2A’ plant first look small and clear, but gradually enlarge, and progressively become ‘milky’ and opaque with continued maturation, finally displaying a desiccated appearance and amber color. In the present disclosure, harvest maturity is defined as the time period between the enlarged clear trichome developmental stage and the opaque/milky trichome developmental stage. Amber trichomes in the ‘CW2A’ plant are an indication of overly mature trichomes. In some embodiments, the harvest maturity of the ‘CW2A’ variety is typically around 15 and ½ weeks after planting vegetative cuttings in the field. Growing conditions throughout the plant’s life cycle, nutrient variations, and environmental factors can all influence the amount of time for ‘CW2A’ plants to reach harvest maturity. The present disclosure uses the terms “maturity,” “harvest maturity,” and “floral maturity” interchangeably. FIGS. 10-13 provide photographs of the ‘CW2A’ plant at harvest maturity.

In some instances, the botanical descriptions disclosed herein reflect the range of phenotypical variation observed under indoor and outdoor growth conditions. Total Potential THC/CBD contents presented in this document reflect the total potential (i.e., decarboxylated) THC and CBD content after decarboxylation of the THCA and CBDA contents of the sample. The formula used for this calculation is reproduced below for the Office’s convenience. Total THC=THC+(THCA*(0.877)). Total CBD=CBD+(CBDA*(0.877)).

When ‘CW2A’ is compared to the feral male parent (a.k.a. ditch weed), ‘CW2A’ is taller in plant height, but narrower in plant width than the feral male parent. The *indica*-dominant feral male parent having a squat stature are shorter than ‘CW2A’ and branch wider with wider leaves than ‘CW2A’.

When ‘CW2A’ is compared to the proprietary female parent (‘1AC’), ‘CW2A’ is taller in plant height, but narrower in plant width than ‘1AC’. Generally, ‘CW2A’ is twice as tall as it is wide, while ‘1AC’ has a similar ratio of plant height to width. ‘CW2A’ with 19-29 teeth of middle leaflet has narrower leaflets than ‘1AC’ with 26-37 teeth of middle leaflet. Regarding petiole length at maturity, ‘CW2A’ is in general shorter than ‘1AC’. Regarding stem diameter at base, ‘CW2A’ is in general shorter than ‘1AC’. When

comparing individual flower length and compound cyme diameter, ‘CW2A’ is smaller in size than ‘1AC’. On the other hand, ‘CW2A’ has generally a longer and thinner stigma than ‘1AC’. While ‘1AC’ does not show hermaphroditic tendency, hermaphroditic plants are observed from ‘CW2A’ depending on growth conditions. Since ‘CW2A’ branches are highly flexible, ‘CW2A’ plants lean over more than ‘1AC’ that has less flexible branches. With regard to time to harvest seeds, ‘CW2A’ shows a shorter harvest time than ‘1AC’. After stem cutting from vegetative and/or flowering plants, adventitious roots of ‘CW2A’ emerge and grow faster than ‘1AC’.

When ‘CW2A’ is compared to the known *Cannabis* plant named ‘ECUADORIAN SATIVA’ (U.S. Plant Pat. No. 27,475), there are several distinctive characteristics. For example, ‘CW2A’ plant is generally taller than the ‘ECUADORIAN SATIVA’ plant. While the aroma of ‘ECUADORIAN SATIVA’ is strongly mephitic with hints of limonene, ‘CW2A’ has an earthy aromatic herbal smell with a hint of citrus and/or pine scent and a general sweetness. ‘CW2A’ stem diameter at base is greater than ‘ECUADORIAN SATIVA’. Also, individual pistillate flowers and stigma of ‘CW2A’ are longer than those of ‘ECUADORIAN SATIVA’. Furthermore, there is a significant difference in total THC content between ‘CW2A’ and ‘ECUADORIAN SATIVA’. The total THC content of ‘CW2A’ is between 0.13-0.27%, rendering the claimed plant a hemp plant under U.S. law. ‘ECUADORIAN SATIVA’ on the other hand, accumulates 12.45% total THC, resulting in a different classification of the plant.

The following is a detailed description of the new cultivar of ‘CW2A’. The following description is for plants that are vegetative and reproductive stages from seedling to 12 weeks old as of the time of the measurements.

General description:

Plant life form and habit.—An herbaceous, upright, dioecious annual plant with hermaphroditic tendencies depending on growth conditions.

Classification:

Denomination.—‘CW2A’.

Species.—*Cannabis sativa* L.

Origin, form, and growth characteristics:

Origin.—Progeny plant derived from a controlled-cross between proprietary cultivar ‘1AC’ as the female parent (i.e., pollen accepter) and Feral Male Parent (i.e., pollen donor), as described in detail above.

Propagation.—The strain is asexually propagated by vegetative stem cuttings as well as stem cuttings from flowering plants.

Propagation ease.—Easy.

Propagation condition.—Adventitious root structures readily form from stem tissue when submerged in rooting media, including soil, rockwool, aeroponics, etc., when adequate amounts of oxygen and moisture are supplied, and ambient temperatures are between 55-75° F. with appropriate lighting conditions.

Plant:

Height.—1-4 m at maturity.

Width.—0.4-2 m.

Vigor.—High (very vigorous).

Time to harvest.—100-135 days.

Pest susceptibility.—Resistant to common viruses and fungal disease.

Genetically modified organism.—No.

Leaf/foliation:

Arrangement.—Opposite in early vegetative growth stages especially on main axis if grown from seed; A tendency toward alternate arrangements on axillary branches once the flowering stage begins or when taken as a vegetative cutting typically observed. ⁵

Shape.—Palmately compound.

Structure.—Serrated margins, lightly acicular to lanceolate leaflets, tapering to an acuminate apex. ¹⁰

Margin.—Jaggedly serrate with each tooth apex angled toward leaflet apex; apical side of tooth is concave and basal side of tooth is convex. ¹⁰

Hair.—Absent.

Leaf (with petiole) length at maturity.—12-24 cm. ¹⁵

Number of leaflets.—3-5 in immature plants, as many as 9 at maturity.

Middle largest leaflet length.—7-15.9 cm.

Middle largest leaflet width.—1.5-2.0 cm.

Middle largest leaflet length/width ration.—About 4:1-8:1. ²⁰

Number of teeth of middle leaflet (average).—19-29.

Color.—Upper side (Adaxial) — 137A (vegetative growth stage before flowering); very close to NN137A (during flowering stage). ²⁵

Color.—Lower side (Abaxial) — Between 146D and 147C (vegetative growth stage before flowering); between NN137D and 147B (during flowering stage). ²⁵

Leaf glossiness.—Very slight sheen, but not glossy. ³⁰

Veins/midrib shape.—Midvein is straight down the middle of each leaflet; Secondary veins are percurrent, branched alternately from midvein, and grow to tooth apex.

Vein/midrib color.—143C. ³⁵

Petiole:

Petiole length.—4.2-8.0 cm.

Petiole color.—Very slightly lighter than 144A.

Anthocyanin color in petioles.—59A to 187A and 187B when present. ⁴⁰

Anthocyanin intensity in petioles.—(i) Total absence to minute but pronounced mixture with normal green coloration on adaxial surface of petiole during vegetative growth stage; (ii) anthocyanin pigmentation on petioles intensifies and covers both adaxial and abaxial surfaces during flowering stage; darker adaxial surfaces are still 59A to 187A; Abaxial surfaces are lighter and less densely colored with a range of coloration 184A; to 180A; to 178A through 178B; to 176A. ⁴⁵

Stipule shape.—Up to 1.0 cm, spinose with a wider base about 1.0 mm or more thick tapering to spinose tip; light green center with white green edges and a folded, v-shape in cross section; sometimes curvaceous growth. ⁵⁵

Stipule length.—0.4-0.9 cm.

Stipule color.—Green portions of stipule vary from 143A to the light yellow white of the edges 4D. ⁵⁵

Stem:

Shape.—Round at maturity; very slightly squared in immature axillary branches and at immature growth stages; finely pubescent and longitudinally furrowed in conjunction with the slightly square shape; in later vegetative stages, still generally rounded in appearance with slight furrowing on more recent stem growth; older growth fuller with lower parts of main ⁶⁰

stem and oldest branches with slightly woody appearance and outer texture.

Diameter.—1.5-4 cm often multiple stems with thinner diameters, depends on nature of initial cutting material.

Color.—Green portions between RHS 144A and 146A at vegetative maturity and during flowering, woody colored tan lower portions of stem are close to 156A-156D.

Pith type.—Thick to woody for a mature main stem pith; but this is highly dependent on the age and/or maturity of the stem.

Inflorescence:

Blooming/flowering habit.—CW2A produces pistillate flowers in axils at nodal points along main axis and lateral branches for most of the vegetative growth period; as flowering begins to develop, these start to become more prolific clusters of individual flowers that appear on increasing branching growth from axillary buds emerging from increasingly short internodes on both the main and lateral axes; observations indicated a noted shift to this pattern between 57-73 days after vegetative clones were transplanted outdoors; the pointed appearance of the terminal inflorescence buds probably contribute to the overall less dense popcorn appearance of floral clusters along the lateral and main axes; some are quite full and denser more similar to 1AC, but many are the looser popcorn appearance.

Inflorescence position relative to foliage.—Above.

Flower arrangement.—Overlapping, Congested, touching, and sometimes stacked.

Number of flowers per plant.—Hundreds to thousands of flowering sites. ³⁵

Flowers:

Shape.—Bilateral symmetry with an overall compressed ovaloid appearance.

Flower (individual pistillate) length.—6-11 mm.

Flower (compound cyme) diameter.—3.0-12.5 cm.

Corolla shape.—No defined corolla.

Corolla color.—N/A.

Bract shape.—Miniature leaf, trichomated, tips of leaflets emergent from dense floral clusters; leaflets number 3 or 5 with many bracts having 5 leaflets; the base pair is nearly vestigial.

Bract size.—2-7 mm or more depending on maturity of flowering spike.

Bract color.—Adaxial — darkest at tips between 139A to lighter at base of leaflets 147A; Abaxial — between 137B and 147B.

Bracteole color.—Vibrant green streak in middle is very close to 141C to thin white papery margins close to 4D, 8D, and 11D.

Stigma shape.—Short apical style with two long filiform stigmatic branches.

Stigma length.—4-11 mm.

Stigma color.—Freshly emergent, tips and papillae 1C-1D to 2D and 4C; some have a slight vegetative greenish hue, 144C to 145A; When senesced, from a darker 165A to a lighter 164A to 165B.

Trichome shape.—Capitate-stalked glandular multiseriate/uniseriate trichomes, especially on flowering inflorescences and perigonial bracts.

Trichome color.—4D, 155A and NN155A-155D.

<i>Cola (terminal bud) shape.</i> —Naked, vegetative, and mixed depending on life stage (vegetative/flowering).	
<i>Cola (terminal bud) color.</i> —Many emergent pistillate flowers, NN137B through 143A-143C, 144B, N144C, 145A-145D, 157A-157D; emergent bract leaflets 147A; freshly emergent stigmas, tips and papillae 1C-1D to 2D and 4C; some have a slight vegetative greenish hue, 144C to 145A.	
<i>Pedicel.</i> —Absent.	5
<i>Pedicel color.</i> —N/A.	
<i>Staminate flower.</i> —Minute or reduced to absent (sessile) in pistillate flowers.	
<i>Sepal color.</i> —10D at end near papery edges with vegetative streaks down center of each sepal, N144B to N144C, depending on maturity.	10
<i>Pollen.</i> —N/A.	
<i>Seed.</i> —Textured, globular, and encased in trichomated leaf-like fused bract (perigonium), solitary, ovoid, and slightly compressed. Seeds weigh 0.01 g-0.02 g each.	15
<i>Seed length.</i> —Typically 4-7 mm in length.	
<i>Marbling of seed.</i> —Medium.	
<i>Petal.</i> —Apetalous (petals absent in flowers, but sepals present on staminate flowers).	20
Other characteristics:	
<i>Aroma.</i> —Earthy aromatic herbal smell with a hint of citrus/pine scent and a general sweetness.	
<i>Proportion of hermaphrodite plants.</i> —Lower (~10%) in vegetative clones; more moderate in populations from seeds harvested from fields (segregating population and not necessarily selfed).	25
<i>Hardiness.</i> —Hardy to tolerate moist and damp conditions without showing stress.	
<i>Breaking action.</i> —Branches are highly flexible. Central stem is strong so that stem breakage usually does not occur.	30
<i>Seed shattering.</i> —About 30-50% of seeds shatter readily if plants are grown in the field.	
<i>Rooting rate after cutting/cloning.</i> —CW2A rooting rate is 95-99% on average; vigorous.	35
<i>Total THC and CBD content at harvest maturity.</i> —(i) Total THC content: 0.13% to 0.27%; (ii) Total CBD content: 4.50% to 6.24%.	
In addition, provided herein are further descriptions of the new cultivar of 'CW2A' CW2A has the following characteristics:	40
Growth Habit:	
CW2A plant has long and slender leaflets/leaves and is 1-4 meters in height at maturity depending on growth conditions ("sativa-dominant"). Monoecious characteristics without stress manipulation are not common, but occasionally observed. Dioecious plant has hermaphroditic tendencies.	45
CW2A also shows premature flowering without change in light duration though it is still responsive to light/dark cycle (12/12 hours) for inducing flowering. Elongated nodes bear palmately compound leaf structures on elongated petioles. Nodes tend to stack in early growth stages and elongate in later parts of vegetative growth. In immature vegetative growth stages, the plant often shows flower primordia or fully formed flower structures as evidenced by pairs of white, hair-like stigmatic tendrils at nodal branch points. Inflorescences are long and spear like indeterminate inflorescences.	50
	55
	60
	65
Flowering and Seed Formation:	
Timing of flowering is largely dependent (if not entirely) on photoperiod.	
Week 1-Week 2	
5 vigorous growth, pistillate flowers are already present, the maturity rate and pistillate flowers grow very rapidly and multiply, pistillate flowers are in prime condition for pollination and beginning seed formation in early flowering stages due to monoecious characteristics.	
Week 2-Week 4	
10 vigorous growth continues, more pistillate flowers grow and begin forming first bud like structure between two and three weeks, pistillate flowers are in prime condition for seed formation up to three and a half weeks.	
Week 4-Week 6	
15 vigorous growth slows down, buds begin to swell, plant has nearly doubled in size from last day of vegetative stage, bud characteristics begin to mature, plant terpenes are at their peak potency at 6 weeks, male staminate flowers begin to form and open (yellow banana shaped sacs).	
Week 6-Week 8	
20 buds begin to swell to full potential, seeds begin to form and mature at internodes and within flower buds, all characteristics are realized, yellowing of the leaves occur naturally, cannabidiol compounds are at their peak at week 8, leaves begin to naturally yellow.	
Week 8-Week 10	
25 leaves dry, leaves and seeds drop, volatile terpene compounds extremely diminish, cannabidiol compounds slowly diminish.	
Growth Conditions:	
Vegetative Stage	
30 75-85 degrees F. is ideal, temps up to 90 degrees F. are not harmful, 40-60% relative humidity.	
Flowering Stage	
35 75-85 degrees F. (nights getting cooler, as low as 40 degrees F.), 40-50% relative humidity.	
40 In another embodiment, temperature and humidity ranges may be decreased or increased to account for all weather conditions.	
Shape of Plant at Maturity:	
45 long and spear like flowers, bushy but elongated branches, height and shape depends on planting pattern, when planted with space (5 feet apart), plant bushes and is 5-6 feet tall, when planted close (2 feet or less apart), plant is longer and more string/spear flower characteristics and be up to 12 feet tall.	
Branching Habits:	
50 dependent upon planting pattern. With sufficient space, the plant forms branches 360 degrees with a concentration of branches forming toward the sun or light source. The branches are long, spear like, and have tendency to break in high winds due to its length (flower and leaf surface area). Node length on branches start very short in early vegetative stage and elongate as the plant matures. Full flower internode length can be up to 3" inches long.	

Rooting Ability:

Roots grow easily under the proper environment starting from propagation that comprises a temperature of about 70-75 degrees Fahrenheit, 50% relative humidity, 35-55% moisture content in the soil or media, and appropriate lighting.

Feeder roots grow 360 degrees, are typically found 3" inches below ground level, and stay in the top 18" inches of soil. Brace roots typically stay within the center of the plant and can go as deep as 3 feet for maximum stability in windy conditions.

Timing of Duration of Flowering Session:

The timing of the flowering duration is dependent on the degrees latitude positioned on the globe. The dates are dependent on the northern or southern hemisphere. Northern Hemisphere is used below:

40-50 degrees latitude typically begins flowering stage July 5-July 15 to full maturity September 10-September 20; 30-40 degrees latitude typically begins flowering stage July 15- July 25 to full maturity September 20-September 30; 15-30 degrees latitude a later and longer flowering duration is assumed; 0-15 degrees latitude flowering will occur any time of the year because of consistent 12-13 hours of sunlight/day.

In another embodiment, temperature and time ranges may be decreased or increased to account for location change.

Botanical Description of CW2A:

Bark:

tan colored with inner bast fibers running vertical between the inner woody core and bark.

Buds:

1"-5" inches thick,
long and resembling spears,
spiral pattern early but much more full bud like structures later on,
medium on density scale.

Blossoms:

occur predominantly in males but are present in nearly all females,
yellow oval sac shapes,
Male sacs open in early flowering stages of week 2 through week 4.

Females will open later from week 4 through week 6.

Leaves

are developed in early vegetative stage,
leaves are jagged, long and skinny,
large leaves, larger leaves if started from seed.

Fruit:

described in the buds,
full essence and character is not recognized until week 6 in flower.

Fragrance:

earthy and light smoky with a hint of piney mint.

Disease Resistance:

resistant to common viruses and fungal diseases,
In the wrong soil conditions, fungal diseases can occur,
susceptible to molds and mildews if grown indoors without proper ventilation and high relative humidity (constantly greater than 60% relative humidity).

Drought Resistance:

more tolerant in clay loams and higher organic content soils.

less tolerant in sandy loams with lower organic content soils.

Cold Resistance:

not resistant to cold though germination and emergence. If the plant is exposed to less than 45 degrees Fahrenheit for longer than 6 hours, shock and much lower germ rate will occur.

more resistant to cold in later vegetative and mature state.

The plant can withstand between 40 and 45 degrees Fahrenheit for long durations but will show signs of stress and cold shock.

very resistant to cold only late in flowering stage with greater root structures. The plant can withstand several days of frost and temperatures as low as 29 degrees Fahrenheit for less than 5 hours. In this condition, the plant will show extreme shock but will not die.

Damp Resistance:

Plant can take moist and damp conditions without showing stress if in outside conditions and planted in the ground.

Plant does not like to be in oversaturated soil for long periods. Stress will occur showing an intense shrinking and curling of the leaves and nodes.

Productivity (Sunlight, Soil, Water):

Sunlight:
too much direct sunlight does not affect the plant in a harmful way.
does need a minimum of 6 hours of direct sunlight for healthy and fruitful flowering cycle.

Soil:

most productive in sandy loams where water can drain easily. This is only most productive with proper irrigation.

pH of 6.8-7.4 is ideal for outdoor farming.

pH of 6.4-6.7 is ideal for indoor and pH of 5.5-5.8 for hydroponic systems.

Water:

Levels of trace minerals are effective and calcium levels of 200-400 ppm. PH of at or close to 7 is ideal for outdoor farming. PH 6.4-6.7 is best indoors and lower for hydroponics.

Precocity (Flowering, Fruiting, or Ripening Early):

Volatile compounds and plant terpenes are at their peak 2-3 weeks before plant maturity.

Cannabidiol compounds peak 2-3 weeks before seed maturity.

Vigor:

Plant shows vigorous growth in late vegetative stage and the most in the first 2 weeks of flowering stage.

Coloration:

deep forest green at optimal health,

Plant shows different discoloration patterns at signs of nutrient deficiency,

yellowing in late flowering stage is natural.

Market Use:

medical drugs

foods (e.g. salad oil, margarine, food supplements, etc.)

drinks (e.g. infused beverages, sport drinks, etc.)

technical products (e.g. oil paints, varnishes, fuel, print inks, solvents, coatings etc.)

personal hygiene products (e.g. cosmetics, soap, shampoo, bath gels, etc.)

hemp-infused pet treats

textile (e.g. apparel, diapers, fabrics, denim, socks, shoes,

fine textiles, twine, rope, carpets, geotextiles, etc.)

building materials (e.g. fiberboard, insulation material, cement blocks, etc.)

The invention claimed is:

1. A new and distinct cultivar of hemp plant named

'CW2A' substantially as shown and described herein.
